CLAIM

The ornamental design for a personal lab table, as shown and described.

DESCRIPTION

FIG. 1 is a perspective view of a personal lab table showing our new design;

FIG. 2 is a front view thereof;

FIG. 3 is a back view thereof;

FIG. 4 is a side view thereof;

FIG. 5 is an opposite side view thereof;

FIG. 6 is a top view thereof; and,

FIG. 7 is a bottom view thereof.

The broken lines in the drawings illustrate portions of the personal lab table that form no part of the claimed design.

1 Claim, 7 Drawing Sheets
